CORPORATION OF NEW JERSEY

SHANK AND BIT PUNCH

Application filed May 4, 1929. Serial No. 360,386.

This invention relates to pinning out devices and more particularly to a shank and bit punch of the type used for reforming the bores in the ends of drill steels and similar working implements having passages for conveying cleansing fluid to the work.

The objects of the invention are to protect the relatively movable surfaces of the shank and bit punch and its support against wear and to assure an adequate supply of lubricant in suitable form to these surfaces.

Other objects will be in part obvious and in part pointed out hereinafter.

In the drawings illustrating the invention and in which similar reference characters refer to similar parts,

Figure 1 is a longitudinal elevation partly in section of a shank and bit punch and its support constructed in accordance with the practice of the invention, and

Figure 2 is a transverse view taken through Figure 1 on the line 2—2 looking in the direction indicated by the arrows.

Referring more particularly to the drawings, the shank and bit punch is designated generally by A and its support by B. The support B may be in the form of a bracket having a flange C through which extend bolts D whereby the support may be secured to a foundation or, as is frequently done, to a drill sharpening machine (not shown).

The shank and bit punch A comprises a percussive element E and a feeding element F. The function of the percussive element, which may consist of the usual cylinder G and a hammer piston H, is to actuate or drive a punch pin J into an article intended to be pinned out, as for instance, a drill steel K having a longitudinal passage L therethrough for conveying cleansing fluid from a rock drill to the hole being drilled.

A suitable support may be provided for holding the drill steel K in axial alignment with the punch pin J. In the drawings a bearing O is shown for this purpose and said bearing is suitably secured to the support B by means of bolts P. The bearing O serves as a holder for bushings Q having a bore R to conform to the shape of the drill steel 50 which they are intended to receive.

The feeding element F comprises the usual feeding cylinder S which is preferably formed integrally with the percussive cylinder G. The cylinders G and S may be of substantially the same length and lie at different elevations and are also off-set with respect to each other.

In order to actuate the punch towards and away from the work the feeding cylinder S is provided with a piston T having a rod U which projects slidably through a back head V of the feeding cylinder and is connected to a bracket W mounted on the rearward end of the support B. Thus arranged the piston T is stationary and in consequence the cylinders G and S are adapted to be actuated relatively to the piston T.

The pressure medium utilized for actuating the cylinders may be compressed air which may be introduced into a central chamber X of a throttle valve Y disposed rotatably in the back head V. The pressure fluid flows from the chamber X in the throttle valve through a port Z, which in one position registers with an inlet passage b leading to the forward end of the feeding cylinder S, and in another position registers with an inlet passage c leading to the rearward end of the feeding cylinder S. In the periphery of the throttle valve Y is an annular groove d of such extent as to afford communication between either of the inlet passages b and c and an exhaust port e leading to the atmosphere.

Suitable devices may be provided to enable the throttle valve Y to be manipulated from a point at the forward end of the punch. That illustrated comprises a lever f pivoted at one end to an arm g on the support B and a link or rod h pivotally connected at one end to the lever f and with its other end to an arm j carried by the throttle valve Y.

With the exception of the specific arrangement of the cylinders as hereinbefore described the parts so far referred to may be of any well known type. They are included herein merely for the sake of illustrating a practical embodiment of the invention and its advantages as applied to a shank and bit punch.

In shank and bit punches a source of difficulty and one which often entails costly replacements is that of wear to which the comparatively expensive parts of the shank and bit punch, such as the cylinders and their support are exposed. A contributory cause of such wear are the scales which form on the work and are scattered about so that they lodge on the punch and what is more objectionable on the bearing surfaces, where, by their abrading action, they speedily render these parts unfit for service. The present invention aims to overcome this undesirable occurrence. To this end the support B is provided with a plurality, in this instance, two bearing surfaces *k* and *o* which lie at different elevations and in planes off-set with respect to each other. The bearing surface *k* lies at a higher elevation than the bearing surface *o* and serves as a support directly beneath the cylinder G and the bearing surface *o* lies directly beneath the feeding cylinder S for which it forms a support.

At the sides of the surfaces *k* and *o* are bevelled surfaces *p* and *q* respectively. These bevelled surfaces cooperate with similar bevelled surfaces *r* of gibs *s* secured to the cylinders G and S for holding the said cylinders in the proper operative position. Preferably shims *t* are disposed between the gibs *s* and the cylinders so that, in the event of wear on the cooperating surfaces of the gibs and the support, shims may be removed for the purpose of adjusting the gibs *s* in both lateral and vertical directions.

Means are provided to protect the cylinders against the effects of wear due to their reciprocatory action relatively to the support. To this end bearing shoes *u* and *v* are disposed beneath the cylinders G and S respectively and to which they may be secured in any suitable manner. The shoes *u* and *v* are preferably of such length that the forward portion of the bearing surfaces *k* and *o* are at all times covered by the said shoes. Preferably the shoes *u* and *v* are of such lengths that in the fully retracted position of the shank and bit punch the forward ends of said shoes slightly overhang the adjacent ends of the bearing surfaces. In this way any scale which may be broken from the work and scattered by the action of the punch pin will be prevented from lodging on the bearing surfaces.

In the arrangement shown means are provided for constantly supplying lubricant in suitable quantities to the cooperating surfaces of the shoes *u* and *v*, the gibs *s*, and the support B. To this end an oil reservoir *w* is formed on one side of the feeding cylinder S and is provided with a threaded opening *x* at one end through which the oil may be introduced into the reservoir. The opening *x* may be normally sealed by a filler plug *y*.

From points near the top and bottom of

the reservoir *w* lead supply passages *z* and 2 respectively. The supply passage *z* opens into a recess or recesses 3 in the bottom of the cylinder G. In the recess 3 is disposed fibrous material 4, as for instance felt, which serves to filter the oil flowing into the recess. Such oil may flow from the recess 3 through a port or ports 5 in the shoe *u* to lubricate the contiguous surfaces of the shoe and the support.

In like manner recesses 6 are formed in the bottom surfaces of the feeding cylinder S to receive oil from the passage 2. In these recesses 6 may also be disposed fibrous material 7 to filter the oil which flows from the recesses to the bearing surface *o* through ports 8 in the shoe *v*.

From the foregoing description it will be observed that the shank and bit punch and its support will at all times be protected against the wear occasioned by the grit and scale usually present in the vicinity of the pinning out operation, and also that these surfaces may be at all times adequately lubricated. This will prolong the life of the parts and any wear which may occur will be on relatively inexpensive parts which may readily and cheaply be replaced instead of on the comparatively expensive elements of the punch.

We claim:

1. In a shank and bit punch, the combination of a percussive cylinder and a feeding cylinder, a support for the cylinders having a bearing surface, and a bearing shoe carried by the cylinders adapted to overhang and slide on the bearing surface and to form a cover for the bearing surface to prevent the lodgement of foreign matter thereon.

2. In a shank and bit punch, the combination of a percussive cylinder and a feeding cylinder, bearing surfaces on the nether portions of the cylinders, a support for the cylinders having bearing surfaces to accommodate the bearing surfaces on the cylinder, and a bearing shoe carried by the cylinder forming a cover for the bearing surface to prevent the lodgement of foreign matter on the bearing surface and adapted to overhang one end of the bearing surface.

3. In a shank and bit punch, the combination of a percussive cylinder and a feeding cylinder off-set with respect to the percussive cylinder, a support for the cylinder having a plurality of bearing surfaces at different elevations, and bearing shoes carried by the cylinders slideable on the bearing surfaces and overhanging them to form covers therefor to prevent the lodgement of foreign matter on the said bearing surfaces.

4. In a shank and bit punch, the combination of a percussive cylinder and a feeding cylinder integral with the percussive cylinder, said cylinders lying in different longitudinal planes, a support for the cylinders

having a plurality of bearing surfaces lying at different elevations, bearing shoes carried by the cylinders slideable on the bearing surfaces and overhanging them to form covers therefor to prevent the lodging of foreign matter on said bearing surfaces, guide means carried by the cylinder and being slidably interlocked with the support, and means for adjusting the guide means with respect to the support.

5. In a shank and bit punch, the combination of a percussive cylinder and a feeding cylinder, a support for the cylinders having a plurality of bearing surfaces lying at different elevations, bearing shoes for the cylinders slideable on the bearing surfaces and forming covers therefor to prevent the lodging of foreign matter on said bearing surfaces, beveled sides on the support, gibs secured to the cylinders and having bevelled surfaces to slidably engage the bevelled sides, and shims between the gibs and the cylinders to permit of lateral and vertical adjustment of the gibs.

20 6. In a shank and bit punch, the combination of a percussive cylinder and a feeding cylinder, a support for the cylinders having a plurality of bearing surfaces, bearing shoes for the cylinders slideable on the bearing surfaces and forming covers therefor to prevent the lodging of foreign matter on said bearing surfaces, recesses in the cylinders, an oil reservoir, supply passages in the cylinders for conveying oil from the oil reservoir into the recesses, ports in the cylinders for conveying oil from the recess to the bearing surfaces, and means in the recesses to filter the oil flowing from the reservoir to the bearing surfaces.

25 7. In a shank and bit punch, the combination of a percussive cylinder and a feeding cylinder integral with the percussive cylinder and lying in a different horizontal plane, a support for the cylinders having a plurality of bearing surfaces lying at different elevations, bearing shoes carried by the cylinders slideable on the bearing surfaces and forming covers therefor to prevent the lodging of foreign matter on said bearing surfaces, recesses in the cylinders, an oil reservoir in the feeding cylinder, supply passage leading from the reservoir to the recesses, ports for conveying oil from the recess to the bearing surfaces, and fibrous material in the recesses to filter the oil during its passage through the recesses.

30 8. In a shank and bit punch, the combination of a percussive and a feeding cylinder, a support for the cylinder having a bearing surface, a bearing shoe carried by the cylinder forming a cover for the bearing surface to prevent the lodgement of foreign matter on the bearing surface and adapted to overhang one end of the bearing surface, bevelled sides on the support, and gibs secured to the cyl-

inders having bevelled surfaces to slidably engage the bevelled sides.

9. In a shank and bit punch, the combination of a percussive and a feeding cylinder, a support for the cylinder having a bearing surface, a bearing shoe carried by the cylinder forming a cover for the bearing surface to prevent the lodgement of foreign matter on the bearing surface and adapted to overhang one end of the bearing surface, bevelled sides on the support, gibs secured to the cylinders and having bevelled surfaces to slidably engage the bevelled sides, and shims between the gibs and the cylinders to permit of lateral and vertical adjustment of the gibs.

In testimony whereof we have signed this specification.
